TRANSPARENT COVERING PANEL FOR LIGHT FITTINGS

Friedrich Clostermann, Hagen, and Hans-Joachim Richter, Neheim-Hüsten, Germany, assignors to Trilux-Lenze KG, Neheim-Hüsten, Germany, a firm

Filed Apr. 29, 1969, Ser. No. 16,945

Term of patent 14 years

Int. Cl. D26—06

U.S. Cl. D48—16

Fig. 2

Fig. 4

Fig. 5

FIG. 1 is a top plan view of a transparent covering panel for light fittings;

FIG. 2 is a side elevational view of the panel seen on one of the corners thereof;

FIG. 3 is a side elevational view of the panel seen on a longitudinal side;

FIG. 4 is a top plan view, on an enlarged scale of one of the repeat units of the panel, the remainder of the panel being omitted for convenience of illustration; and

FIG. 5 is a perspective view thereof.

We claim:

The ornamental design for a transparent covering panel for light fittings, as shown and described.
